UNITED STATES PATENT OFFICE.

THOMAS KERRIGAN, OF MAHANOY PLANE, PENNSYLVANIA.

FUSE CAP.

Application filed July 15, 1922, Serial No. 575,409. Renewed August 14, 1925.

To all whom it may concern:

Be it known that I, THOMAS KERRIGAN, a citizen of the United States, residing at Mahanoy Plane, in the county of Schuylkill and State of Pennsylvania, have invented a new and useful Fuse Cap, of which the following is a specification.

By way of explanation, it may be stated that fuses, used by miners and others, are inserted into a cap. The fuse frequently blows out of the cap, and the present practice is to bite and indent the cap so that the same will retain a hold upon the fuse. The foregoing being understood, it may be stated that it is the object of this invention to provide a simple means whereby a cap may be held on a fuse in a device of the class described.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the invention; Figure 2 is a longitudinal section; Figure 3 is a longitudinal section, looking toward the holding tongue, parts being broken away; and Figure 4 is a transverse section.

The numeral 1 marks a cap of the kind

to which a fuse is adapted to be inserted, comprising a tubular body 2. Openings 5 are formed in the body 2. The openings 5 may be V-shaped and may be disposed opposite to each other, if desired. A 45 portion of the material set free in the formation of each opening 5 constitutes a pointed tongue 6, which is inwardly inclined. The material along the other two edges of the opening 5 may be bent inwardly to form flanges 7 which converge toward each other. When the fuse is inserted into the cap 1, the tongue 6 will prevent the accidental withdrawal of the fuse, and the converging flanges 7 aid the tongue 6 materially in holding the fuse in the cap. 50 55

I claim:—

1. In a device of the class described, a cap provided with an opening, a portion of the material freed in the formation of the opening being extended inwardly to constitute a holding tongue disposed along one edge of the opening, the material freed in the formation of the opening being extended inwardly to form flanges located along other 60 65 edges of the opening.

2. In a device of the class described, a cap provided with oppositely disposed openings, a portion of the material freed in the formation of the openings being extended inwardly to constitute holding tongues disposed along one edge of each opening, the material freed in the formation of the opening being extended inwardly to form flanges located along the remaining edges of the 70 75 opening and converging toward each other.

In testimony that I claim the foregoing as my own, I have hereto affixed my signature.

THOMAS KERRIGAN.
